UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

HAY-CARRIER.

No. 826,095.

Specification of Letters Patent.

Patented July 17, 1906

Application filed September 13, 1905. Serial No. 278,325.

To all whom it may concern:

Be it known that I, HENRY L. FERRIS, a citizen of the United States of America, residing at Harvard, in the county of McHenry 5 and State of Illinois, have invented certain new and useful Improvements in Hay-Carriers, of which the following is a specification.

My invention relates to improvements in hay-carriers, and is fully described and explained in this specification and shown in the accompanying drawings, in which—

Figure 1 is a side elevation of my improved device. Fig. 2 is a section in the line 2 2 of Fig. 3, showing the device tripped. Fig. 3 is 15 a rear elevation of the device. Fig. 4 is a section in the line 4 4 of Fig. 1. Fig. 5 is a horizontal section in the line 5 5 of Fig. 1. Fig. 6 is a top plan of the pulley-supporting member. Fig. 7 is an elevation of one of the 20 frame-sections and the adjacent parts, and Fig. 8 is a section in the line 8 8 of Fig. 2.

Referring to the drawings, A is a track bearing a trip-block a.

B is a carriage running on the track and 25 supported by wheels or rollers b, said carriage having at its lower end a circular turn-table B', upon which is swiveled a frame comprising two side plates C C', riveted or otherwise secured together to form an inclosed 30 structure. The side plate C' is formed near its rear end with downwardly and outwardly projecting ears c, which receive gudgeons d, cast integral with a housing D', containing a stationary main pulley D. This pulley is 35 pivoted upon a longitudinal axis about which it can swing, its axis of rotation extending parallel to the length of the frame. Between the two side sections is pivoted a pulley-supporting member E in the form of a lever of

40 the first order, the said lever being well illustrated in top plan in Fig. 6. At the rear of this lever are two bosses e e', which support, respectively, a gudgeon f and a hollow boss f' at the front and rear of a housing F', carrying 45 a movable main pulley F. It will be seen that this pulley, like the pulley D, is pivoted upon a longitudinal axis parallel to the length of the frame about which it can be swung.

X indicates the rope of my device, the 50 same passing in at the front end of the frame, along over the pulley-supporting member E, down over the movable main pulley F, under two sling-pulleys Y Y', up over the stationary main pulley D, and thence down to the

block of the sling-pulley Y'. By the construction here shown the bight of the rope which supports the sling-pulleys extends across the frame instead of in line therewith. Heretofore to produce this kind of bight in a sling-carrier it has been necessary to place 60 the pulleys at a considerable distance apart if both or either of them extended longitudinally of the frame, and even when this was done the ropes occasionally reached such an angle when pulled out to the edges of the hay-sling as to bind on the edges of the pulley and tend to run off. In my device this is prevented by swiveling both pulleys side by side on horizontal axes, so that they can be swung apart to permit the rope to take any desired 70 angle.

The remaining features of my device are substantially similar both in construction and operation to the corresponding parts shown in my application filed on even date 75 herewith and allotted Serial No. 278,323.

G is the engagement member which strikes the trip-block a. H is the pivoted dog which locks said engagement member and holds the clamping mechanism out of engagement with 80 the rope. I is the upper movable clamping-jaw, which is operated by the pulley-supporting member E exactly as in said application set forth. J is the lever operated by the rise of the sling-pulleys, and K is the fork connecting said lever with the dog H. No detail description will be necessary of these parts, nor will any description of the hand tripping and swiveling mechanism be required.

I realize that considerable variation is possible in the details of this construction without departing from the spirit of the invention, and I therefore do not intend to limit myself to the specific form herein shown and 95 described.

I claim as new and desire to secure by Letters Patent—

1. In a device of the class described, the combination with a track, a frame, a pulley-supporting member, and mechanism for locking and tripping the pulley-supporting member, of a pulley-housing extending longitudinally of said pulley-supporting member and pivoted thereto by its upper part, a second 100 pulley-housing pivoted to the frame beside the first and pulleys within the housings.

2. In a device of the class described, the

combination with a track, a frame, a pulley-supporting member connected with a rope-clamping mechanism, and mechanism for locking and tripping the pulley-supporting member, of a pulley-housing extending longitudinal of said pulley-supporting member and pivoted thereto on a longitudinal axis, and a second pulley-housing pivoted to the device upon a longitudinal horizontal axis 5 and pulleys within the housings.

3. In a device of the class described, the combination with a track, a frame, and a pulley-supporting member centrally pivoted in the frame, of a pulley-housing extending longitudinal

15 gitudinally of said pulley-supporting member and pivoted thereto upon a longitudinal axis, a second pulley-housing also pivoted upon a longitudinal horizontal axis and pulleys in said housings.

In witness whereof I have signed the above 20 application for Letters Patent, at Harvard, in the county of McHenry and State of Illinois, this 6th day of September, A. D. 1905.

HENRY L. FERRIS.
